UNITED STATES PATENT OFFICE.

LEO HECHT, OF NEW YORK, N. Y., ASSIGNOR TO SUN RISE LAMP MFG. CO., INC., A CORPORATION OF NEW YORK.

DESIGN FOR A CANDLESTICK BASE OR ARTICLE OF ANALOGOUS NATURE.

Application filed November 17, 1928. Serial No. 28,920. Term of patent 3½ years.

To all whom it may concern:

Be it known that I, LEO HECHT, a citizen of the United States, and a resident of the city, county, and State of New York, have invented a new, original, and ornamental Design for a Candlestick Base or Article of Analogous Nature, of which the following is a specification, reference being had to the accompanying drawing; forming a part thereof.

The single figure of the drawing shows a perspective view of the candlestick base or article of analogous nature.

I claim:

The ornamental design for a candlestick base or article of analogous nature substantially as shown.

LEO HECHT.
